SEWING MACHINE

Fredric W. Breul, Bridgeport, Conn., assignor to
The Singer Manufacturing Company, Elizabeth, N. J., a corporation of New Jersey

Application September 5, 1945, Serial No. 614,495

16 Claims. (Cl. 112—160)

1

This invention relates to improvements in sewing machines and, more particularly, to sewing machines having work-surfing mechanism for periodically indenting an edge of the work being stitched, thereby to produce in the work a shell-edge effect.

The primary object of this invention is to provide a sewing machine with a simplified work-edge indenting, or surfing, mechanism adapted to lend itself to high speed operation of a sewing machine.

The invention has for a further object to improve the work-feeding characteristics of a sewing machine provided with a work-surfing mechanism.

Another object is to provide a substantially unitary work-surfing mechanism which may be readily applied to a standard type sewing machine with a minimum of alteration and expense.

With these and other objects in view, as will hereinafter appear, the invention comprises the devices, combinations and arrangements of parts described in connection with the accompanying drawings, which illustrate a preferred embodiment of the invention and in which:

Fig. 1 is a front side elevation, partly in vertical longitudinal section, of a portion of a sewing machine containing the improved work-surfing mechanism. Fig. 2 represents a transverse vertical section of the bed-plate of the machine, the section being taken substantially on the line 2—2 of Fig. 1. Fig. 3 is a bottom plan view of the sewing machine; a portion of the bed-plate being broken away. Fig. 4 is a bottom plan view of the presser-foot of the machine. Fig. 5 is a detail view partly showing the presser-foot and feed-dog in side elevation and the throat-plate in section. Fig. 6 is a top plan view of a portion of the bed-plate of the machine, with the cover-plate of the surfing mechanism housing removed. Fig. 7 is a detail view, in front elevation and partly in vertical section, of the surfing blade in its advance position with respect to the presser-foot of the machine; the section being taken substantially on the line 7—7 of Fig. 8. Fig. 8 is a top plan view showing the surfing-blade, its carrier-block, the hemmer-attachment and the work; the presser-foot being illustrated in dot-dash lines.

The present improvements have been embodied in a lock-stitch sewing machine of the class disclosed in the United States patent of S. Zonis, No. 2,267,581, December 23, 1941. The sewing machine has a frame including a bed-

2

plate 10, from one end of which rises the hollow-standard 11 of a bracket-arm terminating in a head 12. Journaled for vertical reciprocation in the head 12 is a needle-bar 13 carrying at its lower end a needle 14.

The needle 14 operates through a suitably apertured throat-plate 15, secured upon and forming with the bed-plate 10 a work-support. Disposed below the throat-plate 15 and complementary to the needle 14 in the formation of lock-stitches, is a rotary loop-taker 16 of the rotary hook type and having a thread-loop seizing beak 17. The loop-taker 16 rotates twice for each needle-reciprocation and casts the needle-thread loops about a mass of under thread contained in a thread-case 18 journaled in the loop-taker and restrained against rotation therewith.

The loop-taker 16 is suitably secured upon one end of a horizontally disposed loop-taker shaft 19 which is rotatably journaled in spaced bearings 20 seated in a horizontally apertured bushing 21. The bushing 21 is secured by a screw 22 in a wall 23 depending from the bed-plate 10; said wall 23 forming a portion of a gear-casing providing a lubricant-chamber 24. At its end opposite the loop-taker 16, the loop-taker shaft 19 carries a spur-gear 25 disposed within the lubricant-chamber 24.

20 In mesh with the spur-gear 25 are teeth 26 provided internally of a flange 27 of a driving gear-wheel 28; said gear-wheel 28 being disposed in the lubricant-chamber 24 and adapted to dip into a supply of lubricant contained in said chamber. The driving gear-wheel 28 is secured by a screw 29 upon one end of a horizontally disposed bed-shaft 30 which rotates once for each needle-reciprocation. The bed-shaft 30 is journaled, adjacent the gear 28, in a bearing-bushing 31 secured in another gear-casing wall 32 depending from the bed-plate 10. Adjacent its opposite end, the bed-shaft 30 is journaled in a bearing 33 seated in a lug 34 depending from the bed-plate 10. Suitably secured upon the outboard end of the bed-shaft 30 is a peripherally grooved pulley 35 engaged by a driving belt 36 of the sewing machine in the usual manner.

25 The work is intermittently advanced across the work-support by a differential feeding mechanism including a main feed-dog 37 and an auxiliary feed-dog 38, both of which feed-dogs operate through suitable feed-slots provided in the throat-plate 15. The main feed-dog 37 engages the work entirely rearwardly of the path of needle-reciprocation and the auxiliary feed-dog

38 engages the work entirely in front of the needle-path. The main feed-dog 37 is suitably secured upon a horizontally disposed main feed-bar 39 and the auxiliary feed-dog 38 is suitably secured upon an auxiliary feed-bar 40 disposed substantially parallel to the main feed-bar 39; said feed-bars extending crosswise of the bed-plate 10 and being respectively provided at the forward ends thereof with forks 41 and 42.

At its rearward end, the main feed-bar 39 is pivotally connected to the upper end of a rocker 43 rising from a main feed-advance rock-shaft 44 disposed horizontally below the bed-plate 10 to extend lengthwise thereof. Engaging the opposite ends of the rock-shaft 44 are pintles 45 adjustably secured in lugs 46 and 47 depending from the bed-plate 10. Secured upon the rock-shaft 44, adjacent the lug 47, is a depending crank-arm 48 connected by a pivot bolt 49 to a pitman 50 having a strap embracing a feed-advance eccentric 51 adjustably carried by the bed-shaft 30. The rearward end of the auxiliary feed-bar 40 is also pivotally connected to a feed-advance rocker 52 rising from an auxiliary rock-shaft 53 disposed rearwardly of and substantially parallel to the rock-shaft 44. The rock-shaft 53 is pivotally supported at its opposite ends by pintles 54; one of said pintles being adjustably secured in the lug 46 and the other of said pintles being similarly secured in another lug 55 depending from the bed-plate 10. Adjacent the lug 55, the rock-shaft 53 is provided with a depending crank-arm 56 connected by a pivot-bolt 57 to a pitman 58 having a strap embracing an auxiliary feed-advance eccentric 59 adjustably carried by the bed-shaft 30. The eccentrics 51 and 59 are disposed adjacent each other upon the bed-shaft 30 and are generally similar in construction to the feed-advance eccentric disclosed more fully in the U. S. patent of W. Myers, No. 2,128,031, August 23, 1938.

The bed-shaft 30 also carries a feed-lift eccentric 60 which is embraced by the strap of a pitman 61. The forward end of the pitman 61 is connected by a pivot-bolt 62 to a depending crank-arm 63 at one end of a horizontally disposed feed-lift rock-shaft 64 mounted on pintles 65 which are adjustably secured in lugs 66 and 67 depending from the bed-plate 10. Clamped upon the opposite end portion of the feed-lift rock-shaft 64 are the split hubs of two feed-lift arms 68 and 69; the arm 68 carrying a roller 70 engaged by the main feed-bar fork 41 and the arm 69 carrying a roller 71 engaged by the auxiliary feed-bar fork 42.

From the foregoing description, it will be understood that four-motion movements are imparted to the feed-dogs 37 and 38; the feed-dogs being raised and lowered in unison by the described connections with the feed-lift eccentric 60, while the work-advancing and return movements of said feed-dogs are derived from the adjustable eccentrics 51 and 59. By adjustment of the respective eccentrics 51, 59, the feed-dogs 37 and 38 may be caused to have unison work-advancing movements, or either to full or stretch the work by imparting differential movements to the two feed-dogs.

In accordance with the present invention, the flange 27 of the loop-taker driving gear-wheel 28 is externally provided with spiral threads 72 to form a worm in driving engagement with the teeth of a worm-wheel 73 which extends downwardly through an opening 74 in the bed-plate 10. The worm-wheel 73 has its hub 75 secured by

screws 76 upon a cross-shaft 77 extending transversely of the bed-shaft 30 and disposed above the bed-plate 10. The cross-shaft 77 is rotatably journaled in spaced bearing-bushings 78 and 79 secured in suitably apertured bosses formed in a generally rectangular housing bracket 80; the bracket 80 rising from the bed-plate 10 and being suitably secured thereupon by screws 81. The top portion of the bracket 80 is closed by a cover-plate 82 secured by screws, as 83; the joint between the bracket and cover-plate being preferably sealed by a suitable gasket.

Also secured upon and for rotation with the cross-shaft 77, within the bracket 80, is an eccentric 84 embraced by the strap at one end of a pitman 85. At its other end, the pitman 85 extends between and is pivotally connected by a pivot-bolt 86 to the laterally spaced crank-arms 87 of a rocking sleeve 88 journaled upon a stub-shaft 89 which is suitably secured in the front and rear walls of the bracket 80. The sleeve 88 has a depending arm 90 which is forked to receive one end of a short link 91 pivotally connected to the arm 90. The link 91 is correspondingly connected by a pivot-screw 92 to one end of a horizontally disposed and endwise reciprocatory slide-bar 93. The slide-bar 93 is journaled in an internal bracket-lug 94 and an external bracket-boss 95 for reciprocation transversely of the line of seam formation of the machine; said slide-bar 93 being disposed above the bed-plate 10 and substantially parallel to the bed-shaft 30.

Secured to the end of the slide-bar 93 proximate to the path of needle reciprocation is a carrier-block 96 having horizontally parallel upper and lower faces and provided longitudinally of the slide-bar with a vertical slot 97. Clamped by a bolt 98 to the carrier-block 96 is an edge-wise vertically disposed work-edge indenting element or hem-deflecting blade 99 having its shank located in the slot 97 and terminating in vertically spaced ears 100 straddling the carrier-block 96. The shank of the blade 99 has a slot 101 elongated transversely of the line of seam formation and entered by the bolt 98, thereby providing for adjustment of the blade lengthwise of the slide-bar. As illustrated in Fig. 7, the lower edge of the blade 99 is substantially in contact with the throat-plate 15 and the upper edge of said blade is downwardly inclined toward the free end of the blade, thereby to provide a narrowed work-engaging edge.

The feed-dogs 37 and 38 are opposed by a presser-foot sole-plate 102 having a needle-aperture 103 disposed rearwardly of and forwardly open to a blade-clearance slot 104 provided in the sole-plate to extend slightly beyond the needle-aperture 103, as shown in Fig. 4; said slot 104 being disposed in alinement with the blade 99. The under or work-engaging face of the sole-plate 102 is preferably laterally stepped by cutting it away throughout the length thereof and from the blade-entrance side of the sole-plate edge to the remote side of the needle-aperture 103, to provide a work-clearance recess 105. In the region of the sole-plate slot 104, the recess 105 is enlarged to form a work-clearance notch 106 preferably extending across the entire width of the sole-plate. The sole-plate 102 is pivotally attached to the presser-foot shank 107 which is secured by a screw 108 to the lower end of a presser-bar 109 endwise movable in the bracket-arm head 12 and spring depressed in a conventional manner.

Disposed in front of the presser-foot sole-plate 102 is a conventional scroll hemmer 110 having its shank 111 adjustably secured by a screw 112 upon the bed-plate 10. The delivery end of the hemmer 110 is located to direct the hem-fold H, formed by the hemmer in the work W, under the sole-plate 102 at the recessed side thereof.

In the operation of the machine, the slide-bar 93 performs one complete reciprocation during the formation of a plurality of stitches, as for example six stitches. During its advancing movement, the blade 99 enters the presser-foot slot 104 and deflects the edge of the hem-fold H inwardly sufficiently far to cause the needle 14 to descend outside the hem-fold and thereby form a stitch extending over the edge of the work. The forward feed of the work, in connection with the action of the presser-foot, the return movement of the blade 99 and the resiliency of the material being stitched results in the needle again penetrating the work in its subsequent descent and until the hem-fold is again deflected by the blade 99. Consequently, the stitched work presents a scalloped or shell-edge appearance, as illustrated in Fig. 8 of the drawings.

As may be best seen from Fig. 4, the horizontal work-clearance notch 106 is located intermediate the ends of the presser-foot, thus to divide the sole-plate into a forward portion 102' and a rear portion 102. From Fig. 5 it may be seen that the forward and rear portions of the sole-plate have respectively cooperating therewith the feed-dogs 38 and 37 which are disposed in tandem relation beneath the presser-foot. Thus the feed-dog 38 is effective to feed the work beneath the presser-foot and the feed-dog 37 is effective to carry the work from beneath the presser-foot.

When the work-edge indenting element 99 is employed, it has a tendency to place the work which is beneath the presser-foot under a strain and thus stretch the same as the work is clamped at both the forward and rear portions of the foot. Therefore, the needle, being disposed directly behind the work-edge indenting blade, penetrates and forms stitches in the stretched portion of work. When the work is free of the presser-foot it will then have a tendency to pucker.

In order to obviate this objectional puckering, the present feed-dogs are timed so that the forward or auxiliary dog 38 is given a longer stroke than that which is imparted to the main or rear dog 37. The forward dog will then feed the work beneath the foot faster than the rear dog can feed it away, and therefore, an abundance of work will be disposed beneath the foot. Thus, when the work-edge indenting blade engages the work there will be no tendency to stretch the same and the stitches will be formed in an unstressed portion of the work.

It is to be understood that the above noted housing bracket or frame 80, when detached from the sewing machine, contains the entire work-edge indenting mechanism. In order to adapt a standard type sewing machine for receiving this substantially unitary structure, it is only necessary to provide the bed-plate 10 with an aperture 74 and to furnish the machine with a special presser-foot and a driving gear-wheel 28.

Thus the present work-edge indenting mechanism comprises a substantially self-contained unit which may be readily applied to a standard type sewing machine without involving any great expense or undue effort.

The described hem-deflecting mechanism is structurally simple and compact, and is particularly well adapted for high speed operation, as the mechanism housed by the bracket 80 is constantly and adequately lubricated by the oil-throwing action of the driving gear-wheel 28 which comprises an actuator common to the loop-taker and the hem-deflector.

Having thus set forth the nature of the invention, what I claim herein is:

- 10 1. In a sewing machine having a frame providing a work-support, in combination, a reciprocating needle, a rotary loop-taker complementary to said needle in the formation of stitches, work-feeding mechanism, a work-edge indenting element mounted for reciprocation crosswise of the line of seam formation in the region of the path of needle-reciprocation, a rotary actuating shaft disposed below said work-support, a driving member 15 carried by said shaft, means operatively connecting said driving member with said rotary loop-taker for rotating said loop-taker at a speed greater than that of said rotary shaft, and means operatively connecting said driving member with 20 said work-edge indenting element for reciprocating the same.
- 25 2. In a sewing machine, in combination, a reciprocating needle, a rotary loop-taker complementary to said needle in the formation of stitches, 30 work-feeding mechanism, a work-edge indenting element mounted for reciprocation crosswise of the line of seam formation in the region of the path of needle-reciprocation, a driving gear-wheel, means for rotating said gear-wheel, operative 35 connections with said gear-wheel for imparting to said loop-taker a plurality of rotations for each reciprocation of said needle, and operative connections with said gear-wheel for imparting to said work-edge indenting element a less number 40 of reciprocations than are imparted to said needle.
- 45 3. In a sewing machine, in combination, a reciprocating needle, a rotary loop-taker complementary to said needle in the formation of 50 stitches, work-feeding mechanism, a work-edge indenting element mounted for reciprocation crosswise of the line of seam formation in the region of the path of needle reciprocation, a driving gear-wheel, a pair of driven gears in mesh with said driving gear-wheel, means for 55 rotating said loop-taker from one of said driven gears, and means actuated by the other of said driven gears for reciprocating said work-edge indenting element.
- 60 4. In a sewing machine, in combination, a reciprocating needle, a rotary loop-taker complementary to said needle in the formation of 65 stitches, a rotary loop-taker shaft, work-feeding mechanism, a work-edge indenting element mounted for reciprocation crosswise of the line of seam formation in the region of the path of needle-reciprocation, a rotary actuating shaft, a driving gear-wheel carried by said actuating shaft, said gear-wheel having an internally toothed flange externally provided with a worm-thread, a pinion-gear carried by said loop-taker shaft in mesh with the internal teeth of said gear-wheel, a worm-wheel engaged by the worm-thread of said gear-wheel, and means actuated 70 by said worm-wheel for reciprocating said work-edge indenting element.
- 75 5. In a sewing machine having a frame providing a work-support, in combination, a reciprocating needle, a rotary loop-taker disposed below said work-support and complementary to said

needle in the formation of stitches, feeding mechanism for advancing work across said work-support, a work-edge indenting element mounted for reciprocation above said work-support and crosswise of the line of seam formation in the region of the path of needle-reciprocation, a driving gear-wheel disposed below said work-support, means for rotating said gear-wheel, operative connections with said gear-wheel for rotating said loop-taker, a driven gear in mesh with said driving gear-wheel and rotatably journaled above said work-support, and operative connections with said driven gear-wheel for reciprocating said work-edge indenting element.

6. In a sewing machine, in combination, a work-support, stitch-forming mechanism including a reciprocatory needle, work-feeding means, an edge-indenting element disposed above said work-support and mounted for reciprocation crosswise of the line of seam formation in the region of the path of needle-reciprocation, a rotary actuating eccentric disposed above said work-support, means for rotating said eccentric, a pitman embracing said eccentric, and a two-armed rocker having one of its arms operatively connected to said pitman and the other of its arms operatively connected to said edge-indenting element.

7. In a sewing machine, in combination, a work-support provided with an opening, stitch-forming mechanism including a reciprocatory needle, work-feeding means, an edge-indenting element disposed above said work-support and mounted for reciprocation crosswise of the line of seam formation in the region of the path of needle-reciprocation, a gear-casing depending from said work-support and providing a lubricant chamber, a driving gear-wheel housed by said gear-casing and adapted to dip into a supply of lubricant in said chamber, a driven gear in mesh with said driving gear-wheel and extending through said opening in the work-support, actuating mechanism disposed above said work-support and operatively connected for reciprocating said edge-indenting element from said driven gear, and a casing housing said actuating mechanism.

8. In a sewing machine, in combination, a work-support, stitch-forming mechanism including a reciprocatory needle, work-feeding mechanism, an edge-indenting element disposed above said work-support and mounted for reciprocation crosswise of the line of seam formation in the region of the path of needle reciprocation, a rotary actuating eccentric disposed above said work-support, operative connections with said eccentric for reciprocating said edge-indenting element, casing means above said work-support for housing said eccentric and said operative connections therewith, a lubricant-supply chamber disposed below said work-support, and means rendered effective upon operation of the machine for rotating said eccentric and for supplying lubricant from said chamber to said operative connections with said eccentric.

9. An edge-indenting unit for sewing machines comprising, a frame, a reciprocatory slide-bar journaled in said frame, a hem-deflecting blade carried by one end of said slide-bar, a cross-shaft journaled within said frame crosswise of said slide-bar, an eccentric mounted upon said cross-shaft for rotation therewith, a pitman embracing said eccentric, means operatively connecting said pitman with said slide-bar for actu-

ating the latter element, and means carried by said cross-shaft for actuating the same.

10. In a sewing machine having a frame including a work-support provided with an opening therein, a reciprocatory needle, and an actuating shaft journaled beneath said work-support; the improvement which consists in the provision of a unitary edge-indenting mechanism removably secured upon said work-support, said unit comprising a frame member, an edge-indenting element mounted within said frame member for reciprocation crosswise of the line of seam formation in the region of the path of needle-reciprocation, a rocker-element mounted upon said frame member for actuating said edge-indenting element, and means carried by said frame for actuating said rocker element, said last named means being adapted to project downwardly through said work-support for operative connection with said sewing machine actuating shaft.

11. In a sewing machine having a frame including a work-support provided with an opening therein, a reciprocatory needle, and an actuating shaft journaled beneath said work-support; the improvement which consists in the provision of a unitary edge-indenting mechanism removably secured upon said work-support, said unit comprising a frame member, an edge-indenting element mounted within said frame member for reciprocation crosswise of the line of seam formation in the region of the path of needle-reciprocation, a cross-shaft mounted within said frame member, an eccentric mounted upon said cross-shaft, means operatively connecting said eccentric with said edge-indenting element, and means operatively connected to said cross-shaft, said last named means being adapted to project downwardly through said work-support opening for connection with said sewing machine actuating shaft.

12. In a sewing machine, in combination, a work-support, a reciprocatory needle, a presser-foot disposed above said work-support and having a sole-plate provided transversely thereof with a work clearance notch which divides the working surface of said sole-plate into forward and rear portions, a pair of feed-dogs disposed in tandem relation directly below said presser-foot for operation through said work-support, said feed-dogs being disposed in cooperative work-feeding relation with the respective forward and rear presser-foot sole-plate portions, means to impart differential feeding movements to said feed-dogs, a work-edge indenting element mounted for reciprocation crosswise of the line of seam formation in the region of said work clearance notch, and means to reciprocate said work-edge indenting element.

13. In a sewing machine, in combination, an apertured work-support, a reciprocatory needle, a presser-foot disposed above said work-support and having a work-clearance notch formed intermediate the ends and transversely of the sole-plate portion thereof so as to divide said sole-plate into forward and rear portions, said presser-foot being provided with a needle-aperture located adjacent said work-clearance notch, a pair of independently operated feed-dogs disposed in tandem relation directly below said presser-foot and beneath the upper surface of said work-support, said feed-dogs being disposed in cooperative work-feeding relation with the respective presser-foot sole-plate portions located at either side of said work-clearance notch, a work-edge indenting element mounted for reciprocation

crosswise of the line of seam formation and positioned in line with said work-clearance notch, and means to reciprocate said work-edge indenting element in a timed relation with said needle reciprocations.

14. In a sewing machine, in combination, an apertured work-support, a reciprocatory needle, a presser-foot disposed above said work-support and having a work-clearance notch formed intermediate the ends and transversely of the sole-plate portion thereof so as to divide said sole-plate into forward and rear portions, said presser-foot being provided with a needle-aperture located adjacent said work-clearance notch, a pair of feed-dogs disposed in tandem relation directly below said presser-foot and beneath the upper surface of said work-support, said feed-dogs being disposed in cooperative work-feeding relation with the respective presser-foot sole-plate portions located at either side of said work-clearance notch, means to impart feeding movements to said feed-dogs, said means being adapted to impart a longer feeding stroke to that feed-dog disposed beneath the forward sole-plate portion of the presser-foot than to the other feed-dog, a work-edge indenting element mounted for reciprocation crosswise of the line of seam formation and positioned in line with said work-clearance notch, and means to reciprocate said work-edge indenting element in a timed relation with said needle reciprocations.

15. In a sewing machine, in combination, an apertured work-support, a reciprocatory needle, a presser-foot disposed above said work-support and having a slot formed intermediate the ends and transversely of the sole-plate portion thereof so as to divide said sole-plate into forward and rear portions, said presser-foot being provided with a needle-aperture located adjacent said slot, a work-edge indenting element mounted for reciprocation crosswise of the line of seam formation and positioned in line with said slot, means to reciprocate said work-edge indenting element within said slot in a timed relation with said needle reciprocations, a pair of feed-dogs disposed in tandem relation directly below said presser-foot and beneath the upper surface of said work-

support, said feed-dogs being disposed in cooperative work-feeding relation with the respective presser-foot sole-plate portions located at either side of said slot, and means to impart feeding movements to said feed-dogs, said means being adapted to impart a longer feeding stroke to that feed-dog disposed beneath the forward sole-plate portion of said presser-foot than to the other feed-dog.

16. In a sewing machine, in combination, an apertured horizontal work-support, a reciprocatory needle, a presser-foot disposed above said work-support and being provided with a horizontal work-clearance notch formed intermediate the ends and transversely of the sole-plate portion thereof so as to divide said sole-plate into forward and rear portions, said presser-foot having a vertical slot formed therein adjacent to and in parallelism with said work-clearance notch and a needle aperture disposed therein adjacent to and rearwardly of said work-clearance notch, a work-edge indenting element mounted for reciprocation crosswise of the line of seam formation and positioned in line with said slot, means to reciprocate said work-edge indenting element within said slot in a timed relation with said needle reciprocations, a pair of feed-dogs disposed in tandem relation directly below said presser-foot and beneath the upper surface of said work-support, said feed-dogs being disposed in cooperative work-feeding relation with the respective presser-foot sole-plate portions located at either side of said work-clearance notch, and means to impart feeding movements to said feed-dogs, said means being adapted to impart a longer feeding stroke to that feed-dog disposed beneath the forward sole-plate portion of said presser-foot than to the other feed-dog.
